UNITED STATES PATENT OFFICE.

LEON REES, OF LONDON, ENGLAND, ASSIGNOR TO MONROE M. SCHWARZSCHILD, OF NEW YORK, N. Y.

DESIGN FOR A DOLL-FACE.

42,881.

Specification for Design.

Patented Aug. 13, 1912.

Application filed February 21, 1912. Serial No. 679,138. Term of patent 3½ years.

To all whom it may concern:

Be it known that I, LEON REES, a subject of the King of Great Britain, residing at London, England, have invented a new, original, and ornamental Design for a Doll-Face, of which the following is a specification, reference being had to the accompanying drawing, forming part thereof.

The figure is a plan view of a doll face, showing my new design.

I claim:

The ornamental design for a doll face as shown.

LEON REES.
